M. P. COONS.

Iron Fence.

No. 11,012.

Patented June 6, 1854.

UNITED STATES PATENT OFFICE.

MATTHIAS P. COONS, OF BROOKLYN, NEW YORK.

RIVET-CLAMP FOR WIRE FENCES.

Specification of Letters Patent No. 11,012, dated June 6, 1854.

To all whom it may concern:

Be it known that I, MATTHIAS P. COONS, of the city of Brooklyn, in the county of Kings and State of New York, have invented an Improved Method of Constructing Lattice-Work, Iron Fences of Corrugated Wire, the specific nature of such improvement consisting of an improved device for fastening and securing the individual rods of a panel of corrugated wire fence to each other without interlocking the rods themselves, whereby a more durable, economical, and elegant article is produced at a greatly reduced expenditure of labor, &c., over the ordinary modes of constructing such fences, some of the most prominent of which are illustrated on the drawings accompanying and making part of this specification in which like letters refer to like parts in all the figures.

Figure 5 shows the method of "lacing" straight wires, now much employed, and the labor incident to this method, as compared with mine, will be too obvious to require any further notice, or more explanation than will be afforded by a glance at that figure.

Fig. 6^x represents a method of constructing fence of flat "strap" iron,—the width of the straps being at right angles to the line of the fence, or panel,—where the angles of the "diamonds," formed by the corrugation in this case employed, are secured by riveting through the straps at their points of contact:—a method not applicable or suitable to round rods or wires, such as I employ, which make as compared with straps (for equal weights of metal) a stronger fence at much less cost. This form of lattice work fence, moreover, renders the application of "rosette" ornaments (so very essential to the "finish" of corrugated iron fences of any description) comparatively difficult.

Fig. 6^y shows a form of corrugated wire fence, wherein the corrugations are secured to each other, so as to constitute a continuous panel by "whipping" or binding them together with finer wire: a method at once unsubstantial, inelegant, and troublesome.

Fig. 6^z represents a method where the wires, as well as being corrugated, are inter-twisted with a single twist, which is usually concealed by a "rosette" ornament in two parts, drawn partially together, from each side of the panel, by a rivet passing through

them and between the parts of the twist. This method of joining the wires, beside the trouble of twisting which at the same time injures them, leaves at each juncture a harbor for rain and snow, causing great oxidation and damage at those points, and consequent injury to the entire structure.

These three last named methods while appearing similar, at least in certain features, are yet quite distinct, in nature and results, from the method I employ, and have been simply introduced as the most ready and exact way of distinguishing the latter from them.

To enable others to avail themselves fully of my improvement I will describe the parts incidental to a panel of fence, as exhibited on the drawing, as also the general nature of their construction, application, and use.

Fig. 1 is a front view of a panel of my improved "Corrugated wire fence," with portions of the upper and lower "saddle" rails, and their accompanying ornaments, and some "rosettes" left off. A, A, are the posts supporting and confining the panel rails, b', b', the upper, and c', c', the lower—into both of which are received the corrugated wires d', d', e', e', and f', f', are the "saddles," whose purposes will be herein-after mentioned; and a', a', are "rosettes," as ornaments merely, frequently employed in the "finish" of lattice work iron fences,—but in my case being of a particular interior form, and while serving equally, as in the cases mentioned, the purposes of ornament, are, moreover, indispensable portions of the structure.

In Fig. 2, B and C give each an end view of the "rail" with a portion of the wire, and a rosette, beneath, and the saddle with its ornament above. At B the "saddle" is secured to the "rail" by means of its top ornaments, which may be screwed, or otherwise passed, through both and fastened; that at C, from its form permitting its ornaments, if desired, to be cast on the "saddle"—which has a groove cast within it, of which the "rail" forms the "tongue,"—thus needs no other fastening to the rail.

Of Fig. 3, D and E, being segments of "rosettes" with the incidental wires passing through, or rather across them, illustrate the adaptation of my rosette to the reception of an extra complement, or series, of wires, and which may therefore be termed

its serial application, as also exemplified at the center of the panel, Fig. 1, and F, Fig. 4, the more ordinary application of my rosette, as seen in the same panel. In further explanation of the "serial" feature, I may remark that by a corresponding arrangement of my "rosettes" in providing an additional number of grooves as in E, Fig. 3, though not necessarily an increased number of rivets, (in fact one such fastening only being required, excepting where a central wire, or ornament, as the arrow seen in Fig. 1, and at D, Fig. 3, is used, when if only for symmetry of design, a pair of rivets becomes desirable), I can introduce an additional series of wires, straight or corrugated, for purposes of ornament or increased strength, almost without increased expense except that of the bare material. It may be remarked that, the grooves are so cast that a certain amount of "clearance" is allowed where they cross the outer edges of the rosettes—(for the greater convenience of fitting different designs, &c.) and more fully to prevent the "working" and possible loosening of the rosettes, I have provided, on the blank, or grooved, side of such segment, the "gouts," and corresponding projections, respectively $o', o',$ and $r', r',$ (Figs. 3 and 4) which,—the two segments being brought and riveted together—covering and receiving each the other, prevent, independently, the motion, in any direction, of the two segments upon themselves.

Fig. 4, represents the two halves of my rosette in perspective; showing the wires, in the one, inserted to half their diameter in the curved grooves, the fastening rivet $s',$ &c.

Now with the different parts thus set forth and distinguished I will describe the very simple process of construction, or the application of those parts. Taking wires of any desirable "gage" and length, "corrugated" or "crimped" to any suitable pattern, (by an improved process and the aid of "flexible dies," not necessary here to describe) I pass the ends of those wires through holes in the upper rail, and also through corresponding holes in the lower "saddle," and the rail beneath, when they are respectively secured by riveting or clenching. The convexities, or angles, of any two adjoining wires being adapted in the process of corrugation to this end, are immediately opposite to each other, in the same plane, and separated only by a small space through which the rivet to be used passes, see Fig. 1, while the similar convexities on the wires at the extremities of the panel, immediately opposite and adjoining the center of the posts, in the line of the panel, are received into grooves purposely cast in the post, or, as in the example at Fig. 1, are simply let into the narrow, angular, space formed by the

interior-converging lines of the "quarter-foil" form of post. The wires having been inserted in and fastened to the rails, as mentioned, the "rosettes" may now be applied by placing either half of the rosette, a' , beneath the panel, which, for the purpose of riveting, &c., is placed flat upon an iron bench, so as to receive the wires into the corresponding grooves—see E, Fig. 3—when the other segment or half of the rosette is placed above, or over the first, their blank faces being opposite and nearly touching, and the last half receiving the wires in like manner, the two are brought "home" to each other by passing through them, and between the two, or more, wires they confine, a rivet which is then riveted in the usual manner.

To secure the general "finish" of my fence, I sometimes introduce what I term a "half rosette," fastened (as described for the whole rosette), and secured upon the corrugated wires where they enter the upper and lower rails.

The lower "saddle," as explained, having been secured to its corresponding "rail," the upper "saddle," as in C, Fig. 2, with its accompanying top ornaments is now slid upon its rail, or, if it be preferred, the saddle may be in form and mode of fastening as at B, Fig. 2. The saddles in all cases serving at the same time the purposes of ornamentation, concealment of the ends of the wires, and general strengthening of both rail and panel. The panels being thus far completed, in the factory, their erection into a fence is very simple; the posts, for instance, being such as shown in the drawing, are properly placed and secured in the ground, and being especially adapted to the purpose, by suitable openings, or mortises, for the rails, &c., the panel is laid between the posts, when the whole are fastened and connected by pins, or other simple fastenings (such being what I generally employ) not necessary here to especially describe.

The fence combined in my improved system being now completed it will be seen to possess numerous important features, among which I may mention the ease of manufacture, being effected almost wholly by steam machinery and casting; the many useful purposes of my rosette, which not only fulfills the customary duties of ornament, but moreover, in my case the very important conditions of yielding additional stiffness to the individual wires by their extension over comparatively, long, immovable bearings therein; the preservation of all the wires of the fence in the same plane, giving consequently "flush," and symmetric, fronts; the capability which the rosette possesses of receiving and confining a series of wires, as previously explained; and the general security of those wires, at the places where

they connect with the rosettes, from abrasion and oxidation, by the firm closing of the joints of the rosettes, first, by riveting, and, afterwards, by a coat of thick paint, 5 which filling up all minor interstices, produces, in the whole, a barrier structure unsurpassed in the advantageous combination of beauty, durability and economy, while wholly free from the many evils and disadvantages which have been proved to exist 10 in lattice work iron fences of ordinary modes of construction, all of which involve the necessity and very troublesome feature of intertwisting or fastening together of the 15 wires themselves, so objectionable, not only as regards labor of construction, but conse-

quent after results, and so effectually averted by the application of my rosette, the latter being more especially designed to that object in particular.

20

Having thus fully described my said invention I claim—

The peculiarly constructed rivet clamp and its application to wire fences or for equivalent purposes, in the manner and substantially for the purposes hereinbefore described and stated.
